Primary Examiner — Michael A Pratt(74) *Attorney, Agent, or Firm* — Andrus Intellectual Property Law, LLP(57) **CLAIM**

The ornamental design for a contoured pistol grip, as shown and described.

DESCRIPTION

FIG. 1 is a front isometric view of a pistol grip incorporating my new design;

FIG. 2 is a left side elevation view thereof, wherein the right side elevation view is a mirror image thereof;

FIG. 3 is a front elevation view thereof;

FIG. 4 is a back elevation view thereof;

FIG. 5 is a top plan view thereof; and,

FIG. 6 is a bottom plan view thereof.

The broken lines shown in the drawing Figures are for the purpose of illustrating portions of the article and form no part of the claimed design.
